UNITED STATES PATENT OFFICE.

GEORGE S. TIFFANY, OF SUMMIT, NEW JERSEY, ASSIGNOR TO TELAUTOGRAPH CORPORATION, OF RICHMOND, VIRGINIA, A CORPORATION OF VIRGINIA.

TELAUTOGRAPHIC APPARATUS.

1,426,233.

Specification of Letters Patent. Patented Aug. 15, 1922.

Application filed February 1, 1918. Serial No. 214,853.

To all whom it may concern:

Be it known that I, GEORGE S. TIFFANY, a citizen of the United States, residing at Summit, county of Union, and State of New Jersey, have invented certain new and useful Improvements in Telautographic Apparatus, fully described and represented in the following specification and the accompanying drawings, forming a part of the same.

10 This invention relates to improvements in telautographic apparatus.

It is the object of the present invention to provide electro-mechanical telautographic apparatus, designed for use in bulletin board and like announcements, in which the lateral movements of the receiving pen are controlled by the transmitting tracer through mechanical connections from the transmitter to the receiver, and in which the 20 movements of the receiving pen to and from its writing surface are controlled by the transmitting tracer through electrical connections from the transmitter to the receiver.

25 Another feature of the invention resides in the combination with the telautographic apparatus of projecting mechanism for magnifying the writing done by the receiving pen and projecting or throwing the 30 same upon a screen, bulletin board or the like.

In the accompanying drawings—

Figure 1 is a side elevation of a combined telautograph and projecting machine embodying the present improvements;

Figure 2 is a plan view of the same;

Figure 3 is an end view of the same, partly in section;

Figure 4 is a vertical section on the line 40 4 of Fig. 3;

Figure 5 is a plan view, partly in section, of the transmitter;

Figure 6 is a vertical section of the same;

Figure 7 is a diagrammatic view of the 45 circuits controlling the electric light apparatus of the projecting machine and the raising and lowering of the receiving pen.

Figures 8 and 9 illustrate a modification hereinafter described.

50 Referring to said drawings—1 represents the base of the machine on which is mounted the transmitting instrument, and 2, 3 a pair of standards rising therefrom on which is mounted the receiving instrument and a

pair of horizontal rods 4, 5, on which is adjustably mounted the projecting mechanism.

The transmitter comprises a pair of levers 6, 7, secured, at their outer ends, to collars 8, 9, loose on a pair of vertical oscillating shafts 10, 11, supported at their lower ends in plates 12, 13 on base 1 (in which standards 2, 3 are also supported) and journaled at their upper ends, in tubular brackets 14, 15, projecting from frame 16 of the receiving instrument. These shafts 10, 11 have fixed to their upper ends bevel gears 17, 18, respectively, forming, with said shafts, part of the connections between the transmitter and receiver, as hereinafter described. 70 Levers 6, 7 have pivotally connected with their inner ends a pair of tracer arms 20, 21, in the converging ends of which is pivotally mounted a tracer 22. Beneath tracer 22 a writing platen 23 is provided and in 75 advance of the latter, that is, towards the front of the machine, there is provided an arm rest 24. Writing platen 23 is pivotally mounted, by means of arms 25 connected with it and extending under arm rest 24, 80 and a rod 26 connected with said arms, in brackets 27 extending upwardly from base 1 (Fig. 5). Platen 23 is mounted so that in a writing operation, it will, under pressure of tracer 22, close a circuit, hereinafter described, from the transmitter to the receiver.

Shafts 10, 11, also have secured to them rock arms 30, 31. The rock arm 30 is loosely connected at one end by a link 32, with the rock arm 31, and at its diametrically opposite 90 end by a link 33 with an arm 34 projecting from tracer lever 7. Levers 6, 7 are also loosely connected together by a two-part telescopic rod 35. The reason for this cross-connection between pen levers 6, 7, is that 95 the position of the receiving pen arms 36, 37, is the reverse of that of tracer arms 20, 21, so that the movements of pen arm 36 are necessarily controlled by tracer arm 21 and those of pen arm 37 by tracer arm 20.

100 It will be observed that, as the tracer 22 is moved laterally, as in ordinary writing movements, pen-arms 20, 21 and levers 6, 7 will be correspondingly moved and shafts 30, 31 oscillated in one direction or another 105 to a greater or less extent, according to the direction and extent of movement of tracer 22.

The receiver comprises a receiving pen 28 mounted in the converging ends of a pair of pen-arms 36, 37, pivotally secured to the inner ends of a pair of levers 38, 39, the opposite ends of which have fixed to them, shafts 40, 41 journaled in the tubular brackets 14, 15, before referred to, in receiver frame 16. These shafts are provided with bevel gears 42, 43, meshing with bevel gears 17, 18, fixed to the upper ends of shafts 10, 11. It will thus appear that as the shafts 10, 11 are oscillated, as just described, by the writing movements of tracer 22, shafts 40, 41, will be correspondingly oscillated and through levers 38, 39, and arms 36, 37, move receiving pen 28 in accordance with the movements of tracer 22, and so as to reproduce the writing performed by the transmitting tracer 22.

20 A recording or writing surface 45 is provided for receiving pen 28, consisting of a sheet of glass, celluloid or other transparent or sufficiently translucent material, set in a suitable framework 46 therefor in frame 16.

25 A source of ink-supply is also provided for receiving pen 28 consisting of a bottle 47 of ink carried by a support 48 detachably connected, by a stud and slot 49, 50, with frame 16. Bottle 47 is provided with a side opening 51 through which receiving pen 28 may be supplied with ink by the movement of the pen into line with said opening and the introduction of the pen-point into such opening. This requires two movements of the receiving pen, during a writing operation, namely, of the pen into position opposite the opening 51 and then into the opening, and these movements must of course be controlled from the transmitter. The first

40 movement is accomplished, through the connections already described, between the transmitter and receiver, by so arranging the bottle 47 that the position of its opening will correspond with the unison position of

45 tracer 22. As the latter is moved to such position, the receiving pen 28 will, through such connections, be correspondingly moved and assume a like or unison position in the receiver, with its point opposite bottle opening 51. The other movement (of the pen point into the opening) is accomplished from the transmitter through other connections, which also "raise" and "lower" the receiving pen or move it from and to its recording surface 45, to begin a new line, make a correction, dot an "i," cross a "t" &c. These other connections will presently be described.

The receiver is supplied with transparent 60 or sufficiently translucent film, preferably cellulose nitrate or cellulose acetate, from a supply 55 carrying a web 56 of such material and loosely mounted on a rod 57 fixed at one end to a tubular bracket 58 extending upwardly from frame 16. This bracket is pro-

vided with a disk 59 for receiving and closing the inner end of a cylinder 60 adapted to be slipped over rod 57 and the web of film thereon, so as to protect this latter from injury by weather, dirt, &c. A thumb nut 70 61 on the outer end of rod 57 holds cylinder 60 in position thereon. Cylinder 60 is provided with a longitudinal slit 62 for the passage therefrom of the film strip, which passes thence downwardly over writing surface 45 and between it and receiving pen 28, to a take-up spool 65. The latter is provided with a longitudinal slit 66 for receiving the leading end of the film strip, so that as spool 65 is turned, it will draw the film strip 75 downwardly over writing surface and present fresh writing portions thereof to receiving pen 28, as they are required. Take-up spool 65 is fast to a rod 66 journaled at its opposite end in brackets 67, 68, depending 80 from frame 16 and at one end this rod is provided with a ratchet wheel 69 engaged by a pawl 70 to rotate it and rod 66 and spool 65 step by step in one direction and by a detent 71 to prevent movement of these parts in the 85 opposite direction. The operation of pawl 70 to so rotate rod 66 and spool 65 and thus feed the film strip downwardly over writing surface 45 is effected from the transmitter through connections comprising a rock-shaft 90 72 journaled in a bracket 73 secured to standard 3, having a handle 74 at its outer end, and connected at its inner end with the lower end of a rod 75, the upper end of which is provided with the pawl 70. On 100 the depression of handle 74, rod 75 is depressed and ratchet 69, rod 66 and spool 65 are rotated one step, so as to feed the film strip one line space over recording surface 45. Rod 75 and pawl 70 are again moved 105 upwardly for the next operation by a coiled-spring 76, the ends of which are connected with rod 75 and rock shaft 72 so as to restore them to normal position.

The connections from the transmitter to the receiver for effecting the movements of the receiving pen 28 to and from its writing surface 45, are mainly electrical. They include, at the receiver a pen-lifting magnet 80, a rocking armature 81 therefor, and a pen supporting rod 82 connected with said armature and supporting the receiving pen. In the deenergized condition of magnet 80, armature 81 and rod 82 are retracted and receiving pen 28, therefore, rests against the 115 film strip 56 between it and its writing surface 45. The energization and deenergization of magnet 80 is controlled by transmitter platen 23, as hereinafter described.

The receiver has associated with it a projecting machine comprising a casing 85 containing electric light elements 86 and adjustably mounted on rods 4, 5, so that it may be moved to and from the writing field or surface 45 of the receiver. Casing 85 is also 120 125 130

provided with a condenser-lens tube 87 mounted adjustably upon rods 4, 5, between the casing 85 and receiving writing surface 45, the lens opening in this tube being in line with the light opening in casing 85 and writing surface 45. In line with lens tube 87 is an objective-lens casing 88 also adjustably mounted on rods.

As the writing surface 45 and the film strip 56 are transparent or translucent, it follows that the writing produced on said strip by the receiving pen 28 will be magnified and projected upon a screen (not shown) by the light transmitted from arc 15 light 86.

The circuit for arc light 86 consists of wire 90, to one carbon of said light, and wire 91, switch 92, wire 93, adjustable resistance 94, and wire 95 to the other carbon 20 element; wires 90, 91 being connected with some convenient electric light service wires.

The energization and deenergization of pen-lifting magnet 80, which, as before stated, is controlled by writing platen 23, 25 consists of wires 96, 97 (the latter containing a resistance 98) contacts 99, 100, and wire 101 bridged across the light circuit just described. Normally, contact 100, which is carried by a pivotally mounted yoke 102, is 30 held in engagement with contact 99, by a spring 103, so that, when switch 92 is closed, pen-lifting magnet 80 is energized and attracts its armature 81, thereby moving pen-supporting rod 82 outwardly and through 35 the latter moving receiving pen 28 away from its writing surface 45 and film strip 56. This is also the position of receiving pen 28, during a writing operation, whenever transmitter tracer 22 is raised from its 40 writing platen 23. As shown, the platen 23 is arranged so as to engage yoke 102 and rock the same to disengage contact 100 from contact 99 whenever transmitter tracer 22 depresses the platen, as it will in writing. 45 When tracer 22 is raised to begin a new line, dot an "i" &c., and platen 23 is thereby relieved from downward pressure, yoke 102 is rocked in the opposite direction, thereby engaging contact 100 with contact 99. Magnet 80 being thus energized, its armature 81

will move pen-support 82, and with it receiving pen 28, away from writing surface 45. Therefore, while tracer 22 is in its lowered or raised position, receiving pen 28 will occupy a like position with relation to 55 its writing field or surface 45. In each position it will follow the lateral movements of the transmitter tracer. Here it may be noted that the unison position of tracer 22 is at the upper left hand corner of its writing field or platen 23 and that the unison position of receiving pen is at the same point in its writing field, so that to ink the latter, all that the transmitter operator has to do is to move the transmitter tracer 22 to unison, and then lower it when the point of receiving pen 28, which has followed the movements of the tracer, will be introduced into inkwell opening 51 and inked.

In the modified apparatus illustrated in 70 Figs. 8 and 9, the pen-supporting rod 82 is omitted, the movement of the receiving pen 28 to and from its writing surface being effected by a spring 105, coiled about a stud 106 fixed to frame 16 and bearing against 75 the outer side of pen lever 39, and an arm 107 mounted to move endwise in frame 16 and connected with armature 81 of magnet 80 and bearing against the opposite side of pen lever 39. When magnet 80 is energized, 80 arm 107, moving with its armature 81, will move receiving pen away from its writing surface and when said magnet is deenergized, spring 105 will move said pen to its writing surface.

What is claimed is:

In a telautograph, the combination with a transmitter and a receiver provided with a tracer and pen respectively, of a pair of suitably supported oscillating shafts provided 90 with gears, gears meshing therewith and connected with the receiving pen, and connections between said shafts and the transmitter tracer whereby the receiving pen is caused to reproduce the writing movements 95 of the tracer.

In testimony whereof, I have hereunto set my hand.

GEORGE S. TIFFANY.
